FORM FOR USE IN MAKING BRICK PACKS

Claude R. Friesner, Loudon Heights, Loudonville, N. Y., assignor to Albany Corrugated Container Corporation, Cohoes, N. Y., a corporation of New York

Application May 3, 1950, Serial No. 159,844

10 Claims. (Cl. 100—1)

1

This invention relates to the art of packaging for shipment such objects as building bricks, fire brick, paving brick, tile, cobble stones, wooden blocks and the like, that is to say, articles of reasonably regular outline, small size and relatively great weight. For sake of convenience the term "brick" will be used herein as generic to all such objects.

The most important object of the invention is to improve the efficiency and decrease the cost of packing and shipping bricks.

Another object of the invention is to facilitate the assembling of large numbers of bricks into compact self-sustained shipping units.

Still another object of the invention is to provide an improved form for use in preparing a package of bricks assembled and bound into a compact stack capable of withstanding rough handling without disintegration and arranged in a form in which loading and transporting operations may be carried out with greatly increased facility and safety.

An important feature of the invention resides in a combined pallet and form by means of which a package having the desired characteristics may quickly be assembled.

Another feature of the invention comprises first forming a plurality of spaced rows of bricks, encasing said rows with tough, flexible material, laying courses of brick on the encased rows to form a compact stack supported at spaced intervals on said cased rows of bricks, and then binding first the stack and then the combination of the stack and supporting rows with metal bands.

Another feature of the invention consists in a rectangular stack of bricks, cased and bound as a unit, and bound to a plurality of spaced rows of bricks serving to provide parallel spaces between rows for the accommodation of the forks of a lift truck.

In addition to the obvious advantages of speedy facile packaging afforded by the features of the invention, it is perhaps equally important that a package of bricks assembled in accordance with the invention is so designed that it can be handled without fear of disruption or chipping of the contents; moreover the complete package consists only of the bricks, a casing of paper board and the retaining bands. In other words, there is no heavy apparatus which adds to the shipping weight.

These and other objects and features of the invention together with incident advantages will be more readily understood and appreciated

2

from the following detailed description of a preferred embodiment thereof selected for purposes of illustration and shown in the accompanying drawings in which:

5 Fig. 1 is a view in perspective of the metal form about which the package is assembled,

Fig. 2 is a view in perspective of the form to which has been added the bottom casing sheet, the bricks which are to form the legs of the brick pack and a portion of the bricks forming the package,

Fig. 3 is a view in perspective showing the assembled brick stack with a portion of the upper casing material in place,

15 Fig. 4 is a view in perspective showing the assembled brick package with all of the upper casing material in place and a portion of the wire binder in place,

Fig. 5 is a view in perspective of a completed package elevated from the form in which the package was assembled,

20 Fig. 6 is a view in perspective of an alternative embodiment of the form constructed of wood and metal.

25 Referring first to Fig. 1, there is provided a base or form on which the bricks are assembled for packing. The form comprises a platform 10 on which are welded or otherwise secured, for example by means of bolts, a series of six parallel rows 11, 12, 13, 14, 15 and 16 of ledges 17 de-

30 signed to serve as supports for casing material and base rows of bricks as shown in Figs. 2, 3 and 4 and at the same time provided for grooves or slots through which binding wire or bands can be passed for the purpose of encompassing the completed package as shown in Figs. 4 and 5.

The ledges 17 are each composed of a bottom member 18, side members 19, end members 20 and upwardly extending parallel walls 22 and parallel walls 22 and 25. Adjacent side and end members are secured at the edge 21 thereof, for example by a continuity of the sheet metal or a welded joint. Alternatively, the ledges 17 may be die-stamped from sheet metal or cast in the

45 form as shown in Fig. 1. Also as an alternative, the bottom member 18 of the ledge 17 may be eliminated and the side members 19 and end members 20 may be welded to the platform 10. Pairs of parallel walls 22 and parallel walls 22 and 25 extend upwardly to a height sufficient to provide upwardly opening channels for casing material and bricks placed in the channels formed by parallel walls 22 and parallel side walls 22 and 25 as shown in Fig. 2. The parallel side walls 22

50 and the parallel side walls 22 and 25 have slots

55

24 reaching to the platform 10 and aligned transversely of the walls for accommodating banding material extending transversely under the base rows of bricks. These channels are open at both ends. The adjacent sides 19 and the ends 20 extend upwardly to a height sufficient to elevate the casing material and bricks above the platform 10 as shown in Fig. 2 to provide grooves or slots for the passage of binding wire or tape under the casing material. The ledges 17 are spaced on the base plate 10 to provide grooves 23 and 24 between the ledges 17. The respective grooves 23 and 24 between opposing ledges 17 are in alignment across the length and breadth of the base plate 10. The outermost side walls 25 and the end walls 26 extend upwardly to a height greater than that of side walls 22 to provide a retainer for the lower portions of the casing material as shown in Figs. 3 and 4. The number of ledges 17 in a given row and the relative lengths of respective ledges 17 are determined by the number and spacing of grooves 24 desired for the passage of binding wires or tapes. The dimensions of the platform 10 and of the ledges 17 are determined in part by the size and shape of the bricks which are to be packaged and in part by the manner in which the bricks are to be placed in the form, for example, on their sides or their faces, and parallel to or transverse with respect to the rows of ledges 17. The space between each pair of parallel rows of ledges 17, for example the space between rows 12 and 13, is determined by the width of the fork of a conventional lift truck employed to elevate the completed package from the ledges 17 as in Fig. 5.

The sheet metal employed in fabricating the platform 10 and the ledges 17 is selected for thickness and strength characteristics to be at least sufficient to support the weight of the load of bricks of the type and quantity for which the form is to be employed, desirably with a safety factor sufficient to insure that the ledges 17 will withstand crumpling or buckling under the weight of the bricks. It has been found satisfactory to use 12 gauge sheet steel for the ledges 17 and 16 gauge sheet steel for the platform 10. Although the form illustrated in Fig. 1 is constructed of sheet metal, any other suitable material may be substituted. The entire form may be stamped or otherwise fashioned from sheet steel, or billets of steel or other metals. Various other types of construction may be employed insofar as they result in a form which will achieve the purpose in substantially the manner provided herein.

Upon the form described in the preceding paragraphs there is placed a sheet 27 of heavy corrugated paper, fiberboard, chip board, or the like, that is to say, a tough flexible material which may be creased and folded without rupturing but which tends to hold its folded shape. The folds are made to form channels as in Fig. 2, conforming to the contour of the channels provided by the side walls 25 and 22 and also by opposing side walls 22 in the interior of the form. Rows of bricks 28 are placed in the outermost channels over the conforming sheet 27 and the end flap portions 29 of the sheet 27 are folded over the rows of bricks 28. A row of bricks 30 is laid transversely in the interior channel formed by the opposing side walls 22. The bricks may be laid on their sides or faces, depending upon the manner in which the form is designed. A full course 31 of bricks is laid

over the flaps 29, the exposed portions of the sheet 27 and the center row of bricks 28, the bricks in the course 31 being laid side by side and parallel to the rows of bricks 28. The bricks in course 31 may be laid flat or on side as desired. In Fig. 2 they are shown on side. Over the course 31 is laid a second course 32 in which the bricks are laid on side and at right angles to the bricks in the first course 31. The next course 33 is laid at right angles to the bricks in course 32. Additional courses of bricks are laid in edge-wise relation and alternating in direction until a package of 500 bricks, more or less, has been assembled as an integral stack.

The next steps in the assembly of the package are illustrated in Figs. 3 and 4 wherein four sheets 34 of corrugated paper are folded about the corners of the stack of bricks and are overlapped to form a continuous casing surrounding the side walls of the stack of bricks. Furthermore each sheet 34 is cut at the corner fold and folded at the top or creased and folded to form a flange 35 which laps over the upper margin of the stack. It will be noted that the vertical and upper horizontal edges of the stack are protected by the casing 34. The outermost sides 25 and the center ends 26 serve as means for holding the corrugated paper in position on the stack of bricks previous to the binding operation. The binding wires 42 are inserted in the grooves 23 and 24 in the space below the stack of bricks and are passed through these grooves from one side of the stack to the other and from the front of the stack to the rear. The binding wire is then drawn upwardly along the respective side walls of the cased stack and then bent over the top where the ends overlap. The wires are then stressed tightly around the stack so that compacting pressure is exerted upon the stack of bricks. The ends of the wires are then twisted to fasten them together as shown at 36 in Fig. 4. In place of wire for binding purposes any banding material such as flat metal strips, pressure-sensitive tape or other forms of binding material may be employed, and the term "band" as used in the present application is meant to include any of these materials.

The package is then complete and may conveniently be elevated from the form as shown in Fig. 5. For this purpose a conventional fork lift truck may be employed. Thereafter the package may be deposited on any level surface. In the completed package the bricks in the lower rows 28 serve as supporting legs or as a pallet integral with the package.

An alternative embodiment of the metal form shown in Fig. 1 is illustrated in Fig. 6. This form comprises three transverse boards 37 to which three timbers 38 are secured while a platform 39 is secured to the upper surfaces of the timbers 38. Two parallel side walls 40 are secured along their lower margins to the outermost of the three timbers 38 and extend upwardly from the plate 39. Each side wall 40 is provided with three downwardly extending slots 41 open at their upper ends and extending down approximately to the level, more or less, of the platform 39. In an alternative embodiment, the platform 39 may be grooved at the location of the slots 41 to facilitate the passage of the bands 42 from one side wall to the other.

Secured to the upper surface of the platform 39 are pairs of parallel side walls formed by opposed angle irons 43 and 44 composed of aligned sections separated, as it were, by slots 45.

Flat parallel spacers 46, also sectioned or slotted, are secured to the base platform 39 at the base of the side walls 40 and contiguous with the flat vertical walls of the angle irons 43 and 44. The package of bricks is assembled on this form exactly as described in conjunction with the metal form as illustrated in Figs. 1 to 5.

As an alternative method of binding the stack of bricks, the bands passing from one sidewall to the other as in Fig. 6 may be laid over the rows of bricks in the channels after the flaps of the sheet material have been folded over. An advantage of the package shown in Figs. 4 and 5 is that the banding or strapping is all done at the same time after the package has been completely assembled.

Although I prefer to use flexible steel wires for the strapping of the package of bricks, I also contemplate the use of flat bands; the wires, however, are less likely to cut through the corrugated paper casing and grind against the edges of the bricks.

The present application is a continuation-in-part of my co-pending application, Serial No. 110,723, filed August 17, 1949, now Patent No. 2,596,071, granted May 6, 1952.

Having thus disclosed my invention, what I claim as new and desire to secure by Letters Patent of the United States is:

1. A form for use in assembling a package of bricks, comprising a platform, pairs of parallel walls extending upward from the platform, each pair of walls defining an upwardly opening channel for receiving sheet material for encasing bricks and adapted to have a row of bricks laid therein to establish encased parallel base rows of bricks, ledges at opposite sides of the bottom of each channel for supporting the base rows of bricks above the platform and spaced apart to define an open-ended groove in the bottom of the channel for receiving banding material under the sheet material and base row of bricks therein, and said walls and ledges having slots reaching to the grooves and aligned transversely of the walls and ledges for receiving banding material extending transversely under the sheet material and base rows of bricks.

2. A form for use in assembling a package of bricks, comprising a platform, three pairs of parallel walls extending upward from the platform, each pair of walls defining an upwardly opening channel for receiving sheet material for encasing bricks and adapted to have a row of bricks laid therein to establish three encased parallel base rows of bricks, the channels being so spaced that the tines of the fork of a lift truck may enter endwise in the spaces between the channels from either of the two opposite sides of the platform at the ends of the channels, each channel being open at both ends for accommodating banding material under the sheet material and base row of bricks therein, and said walls having slots reaching to the bottom of the channel and aligned transversely of the walls for accommodating banding material extending transversely under the sheet material and base rows of bricks.

3. A form for use in assembling a package of bricks, comprising a platform, three pairs of parallel walls extending upward from the platform, each pair of walls defining an upwardly opening channel for receiving sheet material for encasing bricks and adapted to have a row of bricks laid therein to establish three encased parallel base rows of bricks, the channels being so spaced that the tines of the fork of a lift truck may enter

endwise in the spaces between the channels from either of the two opposite sides of the platform in the ends of the channels, ledges at opposite sides of the bottom of each channel for supporting the base rows of bricks above the platform and spaced apart to define an open-ended groove in the bottom of the channel for receiving banding material under the sheet material and base row of bricks therein, and said walls and ledges having slots reaching to the grooves and aligned transversely of the walls and ledges for receiving banding material extending transversely under the sheet material and base rows of bricks.

4. A form for use in assembling a package of bricks, comprising a rectangular platform, three pairs of parallel walls extending upward from the platform defining upwardly opening outer channels along two opposite sides of the platform, and an intermediate upwardly opening channel between the two outer channels, each channel being adapted to receive sheet material for encasing bricks and adapted to have a row of bricks laid therein, thereby to establish three encased parallel base rows of bricks, the channels being so spaced that the tines of the fork of a lift truck may enter endwise in the spaces between the channels from either of the other two sides of platform, ledges at opposite sides of the bottom of each channel for supporting the base rows of bricks above the platform and spaced apart to define an open-ended groove in the bottom of the channel for receiving banding material under the sheet material and base row of bricks therein, and said walls and ledges having slots reaching to the grooves and aligned transversely of the walls and ledges for receiving banding material extending transversely under the sheet material base rows of bricks.

5. A form as set forth in claim 4, wherein the width of each of the two outer channels corresponds to the width of a brick, and wherein the width of the intermediate channel corresponds to the length of a brick.

6. A form as set forth in claim 4, wherein the outer walls of the outer channels extend higher than the inner walls of the outer channels.

7. A form as set forth in claim 4, wherein walls are provided at the ends of the intermediate channel on opposite sides of the groove in the bottom of the intermediate channel, said end walls extending higher than the side walls of the intermediate channel.

8. A form as set forth in claim 4, wherein the outer walls of the outer channels extend higher than the inner walls of the outer channels and wherein walls are provided at the ends of the intermediate channel on opposite sides of the groove in the bottom of the intermediate channel extending higher than the side walls of the intermediate channel.

9. A form as set forth in claim 4, wherein the walls and ledges are formed by a series of members of angle-shape in transverse cross section, each member having a horizontally extending part fixed to the platform forming the ledge and a vertical part forming the side wall of the channel, the members in each series being spaced apart in the direction of the length of the channels to provide the slots.

10. A form for use in assembling a package of bricks, comprising a platform, means establishing parallel upwardly opening channels on the platform, each channel being adapted to receive sheet material for encasing bricks and to have a row of bricks laid therein to establish

encased parallel spaced-apart base rows of bricks with the upper surfaces of the base rows above the platform, each channel having a groove in its bottom of less width than the channel extending the full length of the channel and open at both ends for receiving banding material, the channels and grooves being transversely traversed by cross-passages for receiving banding material transverse to the first-mentioned banding material.

CLAUDE R. FRIESNER.
